UNITED STATES PATENT OFFICE.

HENRY A. MARSTON, OF BALTIMORE, MARYLAND.

SAND TOY.

Application filed April 12, 1921. Serial No. 460,739.

To all whom it may concern:

Be it known that I, HENRY A. MARSTON, a citizen of the United States, resident of Baltimore, in the State of Maryland, have made a certain new and useful Invention in Sand Toys; and I declare the following to be a full, clear, and exact description of the same, such as will enable others skilled in the art to which it appertains to make and use the invention, reference being had to the accompanying drawings, and to letters or figures of reference marked thereon, which form a part of this specification.

The invention has relation to toys, and particularly to sand toys or those for writing or designing or outlining a figure or symbol by a thin stream of sand, the object being to provide an improved pencil for this purpose.

The invention consists in the novel construction and combinations of parts, as hereinafter set forth.

In the accompanying drawings illustrating the invention, Figure 1 shows a perspective view of the pencil, and Figure 2 is a detail sectional view, showing opened position of valve in dotted lines.

In these drawings, the numeral 3 designates the pencil which is adapted to discharge at will a thin stream of sand upon a card or other background, as the hand of the user is guided thereover in outlining the figure or design that the artist may wish to express, the discharge end of the pencil being cone shaped at 4, and a valve lever 5 being fulcrumed to said end of the pencil at 6 and having its lower end normally covering the discharge opening at the end of said cone, the other end portion of said

lever projecting in position to be readily operated to open the valve by the middle finger of the hand of the user as the pencil is grasped between the finger and thumb of the hand as pencils are usually held. The upper end of the pencil has a hinged cover 10, which is thrown backwardly or raised when the sand is to be returned thereto.

The lower end of the valve lever terminates adjacent to and is adapted to assume an opened position out of line with the longitudinal axis of the pencil body and out of the path of sand issuing from the outlet opening in an upright position of the pencil.

The invention is useful in instructing backward children and those not studious, owing to its amusing nature, which adapts it also for the instruction of normal children. Sand or other similar material may be used.

I claim:

A sand pencil, having a hollow elongated body provided with a cone shaped end having an outlet opening the peripheral wall of which is in a plane inclined to the longitudinal axis of said body of the pencil, and a valve lever fulcrumed to said body and having a lower end normally closing and terminating adjacent to said outlet opening and also inclined relative to said axis and adapted to assume an opened position out of line with said axis and out of the path of sand issuing from said outlet opening.

In testimony whereof I affix my signature in presence of two witnesses.

H. A. MARSTON.

Witnesses:

J. M. UMSTADLER,
L. S. RAUBORNE.
